**TEMPERATURE CONTROL FOR ROLLERS
SUBJECTED TO HEAT**

John J. Mayer, Wood-Ridge, N. J.

Application November 24, 1948, Serial No. 61,789

3 Claims. (Cl. 257—95)

My invention relates to temperature control and more particularly to means and/or method for maximizing heat transfer in components employed for treating heated material by the application of a refrigerant to the components.

In machines or apparatus for treating or processing mastic or similar materials, rotating hollow cylindrical rolls are usually employed to gauge a mass or blanket of the material to conform to a specific size or to otherwise treat the material in accordance with a preestablished process. Inasmuch as the temperature of the material being treated or processed is such that it effects heating of the rolls above a temperature deemed conducive to satisfactory processing, refrigerants, for instance, cold water, brine, etc., are utilized and introduced within the rolls for cooling the latter. This invention, in its solution of the problem of heat transfer, involves consideration of numerous factors many of which have been ignored or unrecognized in previous attempts to properly cool mill, calender and other rolls. The function is not to cool the stock being worked by the roll, but rather, to maintain the roll at a low enough temperature so it can be kept in continuous operation without becoming overheated. The metal of the roll conducts heat readily. Therefore the thickness of the roll does not introduce a limiting factor. But the inside surface is of prime importance. For purpose of strength, the rolls have thick walls and consequently the inside surface area of the roll is far less, usually about half, the outside surface area. To maintain heat equilibrium, heat transfer from the inside area therefore must be increased to equal the heat transfer received from the stock by a proportionately greater outside area. Mere flow of fluid within the roll does not attain this desired cooling. Unfortunately an insulative film of the fluid forms on the inside surface of the roll. This is because, as smooth as the inside surface of the roll may seem, microscopically it reveals mountains and valleys which entrap the molecules of the cooling fluid. The films trapped in the valleys quickly become hot, and since they are not constantly replaced with cool films or layers, they quickly form and remain as an insulative film which slows down heat transfer from the roll to the transitory fluid beyond said film. Based on these factors, the present invention presents construction and method primarily directed to the elimination of the insulative film normally entrapped in the valleys of the inner surface of the roll.

In addition to the formation of film due to the valleys in the inner wall surface of the roll, there are other factors the presence of which also tends to form and increase the thickness of the insulative film. One of these film-forming factors is inherent to the roll construction which, because of greater inside diameter thereof than diameter of the fluid outlet, forms a basin or sump wherein a considerable volume of liquid always remains and from which discharge or out-flow takes place from the upper surface and thus lets the lower strata of the liquid remain in a state of quiescence or at the most,

2

affected only by a very sluggish flow toward the exit. The present invention recognizes this inherent detrimental structural and operational characteristic of prior art rolls and provides a means and method of overcoming the same by both creating turbulence in the liquid in the basin-like hollow of the roll and by displacing trapped fluid in the surface valleys while submerged.

Another of said factors, the presence of which tends to form and increase the thickness of the insulative film, is the operation of centrifugal action forcing the liquid against the inner wall of the roll so that a very considerable thickness of the liquid becomes fixed with respect to the roll and just revolves with or follows the roll without dislodgement even when carried to zenith location above the pool in the basin-like hollow of the roll. This centrifugal action is exceedingly detrimental to the cooling procedure, since it not only tends to lodge and retain the fluid more securely and immobily in the valleys in the roll inner surface, but results in a very considerable increase in the film thickness, thereby adding greatly to the insulative effect adverse to the desired heat transfer from the roll to the discharging coolant. According to the present invention, the effects of this centrifugal action are decreased and largely overcome. This objective is achieved by use of jets of cooling fluid having a strong downward velocity carrying the jets through the fluid in the basin-like hollow to the roll inner wall thereby both forming a barrier transverse to the rotational direction of the roll and functioning to extract fluid trapped in the inner surface valleys.

In addition to the essential objects of the invention indicated above, another object of my invention is to provide means of the foregoing described character capable of being incorporated in rolls having bores of a relatively small diameter.

A further object of my invention is to provide means of the foregoing described character capable of being incorporated in rolls already in use without modifying the rolls.

40 An important object of my invention is to provide a roll of the foregoing described character which is so constructed and arranged as to limit the refrigerant content to a predetermined amount and equipped with means effective for agitating the content and to preclude formation of an endless coating path about the interior peripheral surface of the roll.

Another important object of my invention is to provide means of the foregoing described character which is simple in construction, durable in use, efficient in operation, economical in manufacture and easy to assemble and disassemble.

With the above and other objects in view, as will hereinafter appear, the invention consists in the combination and arrangement of parts hereinafter set forth and illustrated in the accompanying drawings from which the several features of the invention and the advantages attained thereby will be readily understood by those skilled in the art.

Referring to the drawings wherein like reference characters designate like parts throughout the several views:

Figure 1 is an elevation of a roll assembly having my invention incorporated therein.

Figure 2 is an enlarged sectional view taken on the line 2—2 of Figure 1.

Figure 3 is a detail sectional view taken on the line 3—3 of Figure 2.

Figure 4 is a sectional view taken on the line 4—4 of Figure 1.

In practicing my invention, as illustrated in the drawings, I employ an elongated hollow cylinder or roll 5 formed with a concentric lengthwise extending bore or cooling chamber 6 defined by a relatively thick peripheral

wall 7 and a pair of end walls 8 and 9 provided with trunnions 10 and 11, respectively. The trunnions are adapted to be rotatably journaled in bearings to permit rotation of the roll which constitutes a component of an apparatus or machine for treating or processing heated mastic material or the like, it being understood that the temperature of the material being treated or processed is such that it causes heating of the roll above a temperature deemed conducive to satisfactory processing.

The trunnion 10 is provided with a centralized opening or passage 12 extending therethrough and having its outer end diametrically enlarged as at 13 and its inner end communicating with the chamber 6 through the end wall 8. The opening 12 constitutes an outlet means or passage having an appreciably smaller diameter than the chamber 6 as a result of which the hollow of the roll forms a sump or basin, in the nadir zone of the chamber, lower than the outlet passage 12 and therefore will retain a pool of the refrigerant or liquid therein. The outer end of the trunnion 10 has secured thereto a stuffing box or gland 13' through which extends a conduit or tubular casing 14 communicating with the end 13 of the passage 12, the stuffing box or gland serving as a seal and permitting rotation of the roll 5 relative to the casing 14. The outer end section of the casing 14 has connected thereto a radially extending outlet pipe 15 and is provided with a radial end wall through which extends a refrigerant supply conduit 20.

The refrigerant supply conduit 20 is provided with a pair of sections 21 and 22 with the section 21 being tubular and extending through the passage 12 into the casing 14. The section 22, which may be structurally integrally formed with the section 21, is disposed within the chamber 6 and is substantially ovato-oblong in transversality to provide pairs of oppositely disposed plane and arcuate walls and has its outer end, adjacent the end wall 9, closed. The arcuate walls constitute side walls 22 which are disposed appreciably out of the axially projected outer circumferential confines of the section 21 while the plane walls constitute spaced upper and lower walls 23 and 24, respectively, and are disposed well within said confines.

The upper wall 23 has mounted thereon a plurality of spaced spray heads 25 of the high velocity type whereby sprayed streams of refrigerant or cooling liquid, under pressure, from the conduit 20, will be impelled against the inner wall of the roll or peripheral face of the chamber in the zenithal zone thereof so forcibly as to penetrate into the valleys of the inner surface of the roll and break up, dislodge and disperse the heat-insulating film. It is to be understood that the spray heads 25 are constructed and spaced in a manner causing the spray streams to fan outward and overlap or intermingle in their approach to the roll wall so that the series of spray streams from the several spray heads will provide an uninterrupted expanse of film-puncturing and dispersing stream throughout the length of the zenithal zone between end walls 8 and 9.

The lower wall 24 of conduit section 22 is provided with a plurality of jet nozzles 26, of the high-velocity type, whereby a row of high pressure jets of refrigerant or cooling liquid from the conduit 20 will be directed toward and will pierce the pool of fluid to the bottom thereof and will forcibly impinge against the inner surface of the roll within the basin or sump, the force of the jets being great enough to both agitate the pool of refrigerant contained within the sump and to also rupture and disperse the film on the wall of the roll at the bottom of the pool. It may also be here mentioned that the spray heads 25 and jet nozzles 26 are arranged at top and bottom respectively of the conduit section 22, and alternate in longitudinal location, and thus coact to resist displacement of the conduit section within the chamber from reactionary force of the ejected streams.

By thus utilizing high velocity jet nozzles, I effectively

disrupt, within the nadiral zone, that portion of the refrigerant which had either become quiescent or which had established affinity toward the surface from centrifugal action or which had established a heat-insulating film next said surface by reason of the depth of the pool, or by reason of the rotation of the roll and centrifugal force or by reason of the inherent presence of valleys in the roll surface. The impinging of the jets against the inner surface of the roll is effected with such force as to deflect the jets laterally over adjacent portions of the surface and thus extend the film-disrupting effect over a considerable area. It is further pointed out that the jets coact together to establish a fluid barrier in a plane radial to and longitudinal of the conduit section and extending from the conduit section to the inner surface of the roll, thereby interrupting or dislodging the film or layers of fluid from following the rotational impulse of the roll under influence of centrifugal retention.

The conduit is eccentrically mounted within the roll and is thus disposed in a plane in parallelism with the axis of the roll and superjacent thereto when the roll is disposed horizontally, as clearly illustrated in the drawings. By thus mounting the conduit in closer relation to the zenithal zone of the chamber, the jet nozzles are not only maintained above the refrigerant in the sump or basin, but a larger flow zone is thereby provided in passage 12 beneath the conduit for the discharge of the refrigerant from the chamber 6 to the casing 14.

In assembling the various components, the heads 25 and nozzles 26 are secured to the walls 23 and 24 respectively, and are inserted, with the conduit 20, through the passage 12 and into the chamber 6. Inasmuch as the passage 12 is of a relatively small diameter with relation to the conduit; in some instances the passage being only $2\frac{1}{2}$ " and the conduit, as ordinarily constructed, approximately $1\frac{1}{2}$ "; it will be apparent that the distances the heads and nozzles project outwardly from the conduit must be less than 1" in order to permit insertion of the conduit with the heads and nozzles assembled thereon. Obviously, in these instances, only relatively small heads and nozzles could be employed and which, in practice, would be inefficient.

However, the specific construction of the section 22 of the conduit as herein disclosed with respect to the spacing of the walls 23 and 24, permits the use of materially larger and more effective heads and nozzles than would ordinarily be feasible in view of the relatively small diameter of the passage and the fact that the rolls are ordinarily of a one-piece cast construction without relatively large removable components to permit access to the chamber 6. It is to be understood, that the refrigerant is introduced into the conduit 20 under an effective pressure and that the overflow of refrigerant from the sump will pass out of the chamber through the passage 12, casing and outlet pipe. In actual reduction to practice, I have ascertained that in comparison with the ordinary method, wherein a roll has incorporated therein a refrigerant supply pipe of ordinary construction equipped with relatively low velocity spray means, that the heat transfer in the same roll having my invention incorporated therein is increased more than five times over the ordinary method and under the same operating conditions. Furthermore, by the use of my invention, coating is not only ruptured and dispersed from the mounds on the surface of the chamber, but actually from within the indentations between the mounds.

It is to be understood that the language used herein and in the claims is intended to cover all the generic and specific features of the invention herein described, and all statements of the scope of the invention which, as a matter of language, may be said to fall therebetween. Furthermore, the terms "inner," "outer," "upper," "lower" and "horizontally" are used in a relative sense for the

purpose of description and not by way of limitation, it being understood, in some instances, that the various components may be arranged in a manner whereby the foregoing terms would not appropriately describe their relative positions.

Without further elaboration, the foregoing will so fully explain the invention that others may, by applying current knowledge, readily adapt the same for use under various conditions of service. Moreover, it is not indispensable that all the features of the invention be used jointly since they may be employed advantageously in various combinations and subcombinations.

It is obvious that the invention is not confined to the herein described use therefor as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. In combination with a heat exchange hollow roll having a peripheral working surface, the temperature of which is to be controlled, and having an inner cylindrical wall the surface whereof has microscopic valleys conducive to formation of liquid film and said roll having partial end walls adapted to retain a pool of liquid in the roll, whereby as the roll rotates part of said cylindrical wall is submerged in and part is above said pool, means for injecting concentrated, high velocity jets of fluid on the submerged part of said wall, and means for directing high velocity sprays of fluid upwardly away from the pool for dispersing film on a part of said wall above said pool.

2. In combination with a material treating roll of a type provided with a cooling chamber defined by a peripheral wall and a refrigerant outlet passage communicating with said chamber above the bottom thereof whereby the nadiral zone of the chamber constitutes a refrigerant sump, said wall having an inner face on which refrigerant introduced into the chamber tends to form a film during rotation of the roll and thus establish a surface seal on said face to render refrigerant, engaging said seal, ineffective for cooling said wall below a definite temperature; a refrigerant supply conduit extending through said passage disposed within said chamber and equipped with refrigerant high velocity spray heads effective for directing refrigerant sprays from said supply means against said

10

face within the zenithal zone of said chamber and with sufficient force to counteract said film, and refrigerant jet nozzles effective for directing refrigerant jets from said supply means through refrigerant in said sump and against said face with sufficient force to agitate refrigerant in said sump and to rupture and remove film on said face, whereby, refrigerant from said supply means is rendered effective for cooling said wall below said temperature, said heads and nozzles being arranged in opposed relation to counteract reaction by said sprays and jets and maintain said conduit against displacement.

3. In combination a heat exchange hollow roll having a peripheral working surface, the temperature of which is to be controlled, means for distributing a cooling fluid within the roll comprising an inlet conduit positioned within the hollow portion of the roll and spaced from the inner surface thereof, the said conduit being provided with a plurality of spaced, aligned high velocity spray heads on one side thereof and with a plurality of spaced, aligned high velocity jet nozzles on the lower side thereof; means positioned at an end of the roll whereby the cooling fluid may be drained from the roll, the said means comprising a trunnion having a passage extending therethrough communicating with the hollow portion of the roll, the diameter of the passage being smaller than the diameter of the hollow portion of the roll to provide a sump within the roll, and the diameter of the passage being larger than the external diameter of the conduit; and wherein a stuffing box is secured to the outer end of the trunnion, through which box extends a casing provided with a drain outlet and having substantially the same internal diameter as the trunnion passage and communicating therewith; and wherein a portion of the conduit is positioned centrally of the casing and trunnion passage to thereby permit fluid from the roll to be discharged through the trunnion passage, casing and outlet pipe.
